UNITED STATES PATENT OFFICE.

JOHN JOHNSTON, OF WOONSOCKET, RHODE ISLAND, ASSIGNOR OF ONE-HALF TO GEORGE H. BRIDGE, JR., OF PROVIDENCE, RHODE ISLAND.

BOBBIN HOLDING AND GRIPPING DEVICE.

1,193,901.

Specification of Letters Patent.

Patented Aug. 8, 1916.

Application filed September 15, 1915. Serial No. 50,881.

To all whom it may concern:

Be it known that I, JOHN JOHNSTON, a citizen of the United States, residing at Woonsocket, in the county of Providence and State of Rhode Island, have invented a new and useful Improvement in Bobbin Holding and Gripping Devices, of which the following is a specification.

This invention relates to certain new and useful improvements in bobbin holding and gripping devices, and has for an object to provide a structure embodying simplicity and practical features which render the invention efficient in use.

15 A further aim resides in firmly securing the gripping device in a socket formed in the shuttle to which the former is applied.

The invention has for another object to provide a pivotally mounted bobbin holder and a frictional gripping device to engage with and retain the holder operative within the shuttle.

20 In the drawings—Figure 1 is a fragmentary plan view of a shuttle embodying the present invention. Fig. 2 is a vertical longitudinal section thereof, with a portion of the shuttle left in elevation. Fig. 3 is a horizontal section taken about on line 3—3 of Fig. 2, and Fig. 4 is a fragmentary perspective of the bobbin holder.

The invention is seated in a socket 1 extending from one end of the bobbin cavity 2 of shuttle 3 and consists of an anchor block 4, the spaced gripping plates or arms 5 and the pivotally mounted holder 6 for the bobbin 7. The gripping arms 5 have parallel end portions 8 embracing the anchor block 4 and extend inwardly toward the bobbin cavity to constitute spaced supports between 35 which the holder 6 is pivotally mounted by pin 9. A screw bolt 10 is passed through the shuttle, anchor block and terminals 8 to secure the latter and block within the socket 1, while the pivot pin 9 extends 40 through the terminals 8 into the shuttle body, as depicted in Fig. 3. Thus the rear end of the gripping device is secured firmly and rigidly in the socket by the pivot pin and the screw bolt.

45 50 From the parallel terminals 8 the arms diverge as at 11, and then are deflected within the bobbin cavity to lie parallel with

each other and in spaced relation to the side walls of the cavity as illustrated in Figs. 1 and 3. The inner or opposing faces of the 55 free parallel terminals are provided with series of parallel vertical grooves or seats 12 for a purpose hereinafter described.

The inner end of anchor block 4 is provided with a curved seat 13 on which the 60 hemispherical face 14 of the pivoted end of the bobbin holder 6 bears. The holder is also provided with a downwardly extending shoulder 15 adapted to abut the anchor block to support the holder horizontally and 65 extending upwardly from the holder is a cam 16 pressed against by a flat spring 17. This spring serves to retain the holder in operative and inoperative positions and is secured to the anchor block by screw 18. 70

The bobbin 7 is slidably received on the holder 6 and is formed with an enlarged base 19 peripherally grooved to form seats for rings 20.

75 The distance between the free terminals of gripping arms 5 is slightly less than the diameter of rings 20, therefore, the base 19 of the bobbin will have to be forced between the arms in order that the rings 20 may engage in the seats 12, the arms yielding or 80 springing apart to permit of such insertion of the bobbin. Thus, the latter is frictionally engaged between the gripping arms and retained against any movement whatever. 85

In practice, the holder is swung to the dotted line position depicted in Fig. 2 and a new bobbin placed on the holder 6. A shoulder 21 is provided on the latter to support the bobbin when in this position. 90 The holder, with its bobbin is then swung down into the cavity 2 whereby the base 19 and its rings 20 are forced between the gripping arms 5 and engaged in seats 12. The arms tightly grip the bobbin to prevent any 95 sliding on the holder and consequently securely hold the former within the cavity.

Having thus described my invention, I claim as new and desire to secure by Letters Patent—

100 In a shuttle, spaced gripping arms, an anchor block positioned between the arms, a bolt passing through the gripping arms and anchor block for securing the same to

the shuttle, a bobbin holder having one of its ends positioned between the arms, a pivot pin extending through the arms and bobbin holder, a spring engaging the bobbin holder and anchor block, and means extending through the spring and into the anchor block for holding the spring in position.

In testimony whereof, I have signed my name to this specification in the presence of two subscribing witnesses.

JOHN JOHNSTON.
